(57) **CLAIM**

The ornamental design for a golf bag double strap, as shown and described.

DESCRIPTION

FIG. 1 is a perspective front elevation view, folded as worn, of a golf bag double strap, showing my new design;
FIG. 2 is a front elevation view thereof;
FIG. 3 is a rear elevation view thereof;
FIG. 4 is a right side elevational view thereof, the left side elevation view being a mirror image thereof;
FIG. 5 is a bottom plan view thereof; and,
FIG. 6 is a top plan view thereof.

The broken lines are for illustrative purpose only and forms no part of the claimed design.
